Inventor

Curtis Mc Farland

UNITED STATES PATENT OFFICE

CURTIS MCFARLAND, OF FELICITY, OHIO

SPRING WINDING AND SETTING TOOL

Application filed April 20, 1929. Serial No. 356,863.

This invention relates to a tool which is used by watch manufacturers and repair men for the purpose of setting springs in the spring cases of watches and the like. This is 5 a very awkward and difficult operation because of the very small size of the parts to be handled and because of the difficulty to be experienced in getting the spring properly placed on its arbor without being in continual danger of the spring, springing out 10 either at the arbor or from the upper portion of the spring case during the operation of setting the spring therein.

An object of my invention is to produce an 15 improved tool in which springs of all sizes for watches or clocks may be accommodated and in which such springs may be wound very quickly on a temporary arbor and thereafter placed in their mounting cases 20 without the least trouble.

This and other objects are attained in the tool described in the following specification and illustrated in the accompanying drawings, in which;

25 Fig. 1 is a composite view of the parts of a tool embodying my invention, separated more clearly to show the construction thereof.

Fig. 2 is a perspective view of a spring, typical of the type I have chosen to which to 30 adapt my improved tool, the spring being shown in a somewhat expanded position, with the inner and outer ends thereof pulled outwardly in order to disclose the characteristic means which is usually employed as a fastening 35 at the end of the spring.

Fig. 3 is a view partially in section and elevation, showing the tool embodying my invention the improvements of which I will describe, with a spring mounted therein and 40 in the condition it assumes after having completed the winding operation.

Fig. 4 is a view, similar to Fig. 3, but showing the winding element of the tool removed and the setting element of the tool in position 45 relatively to a watch spring case, ready to place the spring therein.

Fig. 5 is a similar view as that of Fig. 4, but showing the element as having discharged the spring into the spring case.

50 I am aware of the fact that a tool of the

general type I have disclosed, is not new and that such tools have embodied, generally speaking, such elements as the setting element, shown at the left in Fig. 1, and the winding element, shown at the right of Fig. 55

1. However, it is the winding element only to which I have applied the novel features of the invention I am about to describe. In such tools of this type as are available on the market, the winding element is adapted to

use with but one size of spring and great difficulty to the operator in the endeavor to release the end of the spring from the fastener on the winding element is encountered,

with much loss of time, and the abuse to the end of the spring with pliers to release the end from the winding element; therefore, applicant knowing the difficulties encountered

in the art of spring setting, has so changed this winding element that not only more than 70

one size spring can be accommodated thereon, but also to release the fastener from the spring end, without the usual difficulties or abuse thereto. The shaft of the present

winding element is provided with a projecting pin adapted to engage the opening in the inner end of the spring to be wound, so that the spring, as the handle of the winding element is turned, will be drawn into the housing of the setting element. In these 75

tools no provision has been made for rendering the construction adaptable to different sizes of springs, neither from releasing the spring conveniently, after it has been wound.

In the tool I have disclosed, the setting element 6, as has been said, is identical with the setting element usually found in such tools, but the winding element 7 is different. The shaft 8 of the winding element is made movable to adjusted positions in which it may be 80

locked by screw 9. This shaft is also made with a series of offsets of varying diameters 10 and 11 which form the shanks upon which the springs are wound. The smaller shank 11 fits, of course within the recess 12 of the

longitudinally reciprocable plunger 13 of the spring setting element so as to form a bearing for the winding element. The shaft 8 is slotted longitudinally to contain a latch 14 which is pivoted at a point 15 at the end of 95

the shaft and extends outwardly beyond the crank 16 to form a small handle 17 by which the latch may be raised or lowered in the slot 18. On this latch are two pins, projections or lugs 19 and 20, the former extending above the periphery of offset 10 and the latter extending above the periphery of offset 11 of the winding element shaft when the latch is in the raised position shown in Figs. 1 and 3, 10 but which lie below the surface of the offsets when the latch is pushed downwardly to the bottom of its mounting slot. The purpose of these lugs 19 and 20 is to engage within the opening 21 in the inner end of a coil spring 15 such as is shown in Fig. 2, so that as the handle 22 of the winding element is rotated, the spring is drawn in to the housing 23 of the setting element 6, through the slot 24 in the setting element.

20 If the diameter of the inner opening of the spring is too small for offset 10, then set screw 9 is released from the shaft 8 and it is slipped forward into the winding element to render only offset 11 and lug 20 usable. 25 Dpressions 25 in the shaft 8 at properly spaced intervals, afford the means by which set screw 9 locks the shaft in its required positions of adjustment. After the spring winding has been completed, the latch handle 17 is moved 30 downwardly to withdraw the one of the lugs 19 or 20 which is causing the spring to be wound, thereby releasing the spring and permitting the entire winding element to be withdrawn from the setting element.

35 The setting element has a plunger plate 26 suitably mounted within its housing 23 for control by the reciprocable plunger 13 so that when the spring is being wound as shown in Fig. 3, and at the time it is ready 40 for discharge into the spring case, it occupies a position against the rear wall of the housing. In this position the end of the plunger extends beyond the element 6 to form a push button 27 which may be pushed by the 45 user of the tool in order to cause the plunger to force the plate 26 toward the open end of the housing, thereby discharging the 50 spring into the spring case 28 as shown in Fig. 5. This latter description of the setting element does not incorporate anything of especial novelty inasmuch as the entire setting element is of usual construction.

Having thus described my invention, what I claim is:

55 In a combined spring winding and setting tool, the combination of a spring setting element to receive a spring, and a winding element for cooperation therewith, said winding element consisting of a crank, an adjustable shaft therein slotted to receive a lugged latch, said shaft having more than one offset of varying diameter with the slot extending into each offset, and a lugged latch pivoted 60 therein extending beyond the crank for movement, the lugs of the latch cooperating in said

movement with the offsets on said shaft, whereby movement of said latch engages or releases a spring located in said setting element.

In witness whereof, I affix my signature. 70
CURTIS McFARLAND.
